UNITED STATES PATENT OFFICE.

UZAL HULL AND WILLIAM W. MC EWAN, OF BELVIDERE, NEW JERSEY,
ASSIGNORS TO THE NEW YORK WOOD FIBRE COMPANY, OF SAME
PLACE.

PROCESS OF MAKING PAPER PAILS.

SPECIFICATION forming part of Letters Patent No. 445,143, dated January 20, 1891.

Application filed December 12, 1889. Serial No. 333,435. (No model.)

To all whom it may concern:

Be it known that we, UZAL HULL and WILLIAM W. MC EWAN, citizens of the United States, and residents of Belvidere, in the county of Warren and State of New Jersey, have invented certain new and useful Improvements in Processes of Making Paper Pails; and we do declare the following to be a full, clear, and exact description of the invention, such as will enable others skilled in the art to which it appertains to make and use the same, reference being had to the accompanying drawings, and to letters of reference marked thereon, which form a part of this specification.

Figures 1 and 2 are vertical central sections of the apparatus for carrying out our process.

This invention has relation to means for facilitating the manufacture of paper pails; and it consists in the novel process herein-after set forth,

In carrying out this invention apparatus is employed, and in the accompanying drawings I have illustrated certain devices which may be used.

The letter A designates the base-block or press-head, which usually consists of a lower cylindrical portion A', surmounted by the cone-frustum a, the top a' of which has a shallow concave form, and is provided with channels a'', converging to the central opening a''', from which leads the drain pipe or leg A''', which may extend to the level of the lower surface of the base-block A. For some pails I may use a base-block having its upper portion cylindrical. Upon the upper portion of the base-block or press-head is placed the removable holder B, consisting of a sheet-metal covering having its upper edge turned inward to form a small flange b, and having its lower or skirt portion b' extended below the level of the lower edge of the paper-pail blank, so that it can be readily manipulated in lifting the pail from the base-block when finished. The holder is divided or cleft along one side, as shown.

Upon the concave top of the base-block is placed a wire-cloth guard and strainer-piece C, also of concave form to correspond with the

contour of the top a', the wire-cloth serving to provide a surface upon which the paper of the inwardly-bent portion of the side wall and of the bottom center disk, when used, can be pulped and pressed, also providing a strainer-guard to prevent the pulp from passing down into the draining-channels of the press-head, while allowing the water to pass freely through into the same to be conveyed off through the pipe A'''. The small inwardly-turned flange b of the sheet-metal holder B engages the edge of the concave wire-cloth guard and holds the latter down to its proper position upon the top of the base-block A.

In carrying out the process a hollow tube or shell D, of wet paper, is pressed in form and placed upon the removable holder B in such a manner to have its upper edge extend above the top of the base-block a sufficient distance to admit of bending or turning said edge downward and inward in a folded or plicated manner toward the center of the top of the base-block. The extension of the tube is then bent down to form the inwardly plicated flange, which, however, extends more or less toward the center from the bend at d, and sometimes leaves a central opening d', which is to be fitted with the circular center disk, as at E, the circumscribing edge of this disk meeting the plicated edge of the flange portion of the side wall. The side wall is confined to its proper position upon the removable holder by the bandage F, of sheet metal, which is provided with an extension F' of its upper portion, said extension rising above the level of the top of the base-block A. The plicated bottom portion is then pierced or picked, as herein-after set forth, to reduce it to a homogeneous pulp and intimately commingle and lock the fibers, and finally the pulp and picked portion is pressed to give the bottom proper density and shape. The circular center disk of paper is wet, as is also the plicated flange of the side wall which is bent over and down to meet it, and in the operation of joining parts by pulping, water is freely supplied within the cylindrical chamber bounded by the extension F'. In reducing the plicated flange of the paper side wall and the bottom center disk when used to the

proper pulpy consistence a perforating tool or needle-instrument (indicated at G) is preferably employed, this being worked by a picking action into the plicated flange and 5 marginal portion of the center disk until the two are reduced to a pulpy and homogeneous condition.

H is a cloth-binder, which is applied over the pulped portions and held in a strained 10 and secure manner by the pressure of the conical jacket F. This binder serves to prevent the pulp from working out or bulging under the action of the follower K in the pressing operation and assists materially in 15 giving the bottom its proper form.

The follower K is provided with a convex lower or pressure face k', which is usually channelled, as at k'', for drainage, the channels leading to the central aperture K'' of 20 the follower, which is in communication with the pipe K''' of a suction-pump. In this manner it is designed to provide with additional means for removing the water expressed from the pulped parts during the descent of the 25 follower in pressing said pulped parts to give the proper contour to the bottom of the pail. After the pressure the follower is raised and the bandage F removed. The cloth-binder H is taken off and the paper pail lifted from the 30 base-block by means of the removable holder B, whereof the skirt or extension b' below the angle of the base-block affords a purchase or hold for manipulation. This holder, being cleft, is easily loosened and lifted from the 35 base-block, and is as readily loosened from and taken out of the finished pail.

What we claim as our invention, and desire to secure by Letters Patent, is—

1. The process of making paper pails, consisting in, first, forming a wet-paper tube; second, bending inward the end portion of said wet-paper tube, thereby providing a plicated flange portion around the bottom center; third, picking said plicated flange portion, thereby reducing it to a homogeneous pulp the fibers of which are intimately commingled and locked together, and finally pressing the pulped and picked portion to expel the water and give the proper density and shape to the bottom thus provided, substantially as specified. 45

2. The process of making paper pails, consisting in, first, forming a wet-paper tube; second, bending in the end portion of the same, thereby providing a plicated flange 50 surrounding a central opening and applying within said central opening a bottom center disk of wet paper; third, picking said plicated flange and bottom center disk, thereby reducing them to a homogeneous pulp the 55 fibers of which are intimately commingled and locked together, and finally pressing the pulped portions to expel the water and give the proper density and shape to the bottom thus provided, substantially as specified. 60

In testimony whereof we affix our signatures in presence of two witnesses.

UZAL HULL.

WILLIAM W. MC EWAN.
